UNITED STATES PATENT OFFICE.

EDWARD Q. WILLIAMS, OF SYRACUSE, NEW YORK, ASSIGNOR TO THE CONNECTICUT TELEPHONE & ELECTRIC COMPANY, INCORPORATED, OF MERIDEN, CONNECTICUT, A CORPORATION OF CONNECTICUT.

ELECTRICAL-IGNITION SPARK-COIL FOR GAS OR VAPOR ENGINES.

No. 884,116.

Specification of Letters Patent.

Patented April 7, 1908.

Application filed December 28, 1904. Serial No. 238,612.

To all whom it may concern:

Be it known that I, EDWARD Q. WILLIAMS, of Syracuse, county of Onondaga, State of New York, have invented new and useful 5 Improvements in Electrical-Ignition Spark-Coils for Gas or Vapor Engines and for Analogous Purposes, of which the following, taken in connection with the accompanying drawings, is a full, clear, and exact description.

10 My invention comprises certain improvements particularly adapted for use with gas or vapor or hydro-carbon motors, used upon vehicles, boats or for other purposes.

My improved spark coil comprises first, a 15 separate spark making section or element for each cylinder of a multiple cylinder engine, said sections being constructed and arranged to be placed side by side within an outer case, each nearly complete in itself, identical and 20 interchangeably removable, with connections and attachments in such manner as to facilitate adjustments, removal, interchange and efficient operation.

My improvements also comprise an im- 25 proved combination battery switch, a current interrupting vibrator, a support and adjustment thereof, and a removable bridge, as will be hereinafter more particularly described.

30 My improvements are confined to these parts, the remaining portions being of the usual or any preferred form, hence are not herein more fully described.

In the accompanying drawings, Figure 1, 35 is a front perspective view, the case being partly broken away, and one element partly withdrawn. Fig. 2, similarly represents a sectional view through one coil or element showing the electrical connections and fas- 40 tenings. Fig. 3, is a partial section of the case and switch connections. Fig. 4, is an inverted plan of the switch. Fig. 5, is an inverted plan of the bridge. Fig. 6, is an inverted plan of the contact spring. Fig. 7 45 is a diagrammatical illustration of my improvement, consisting of a double coil as used in an upright dash board position with cover on; also batteries and double cylinders 73, 74, of an engine connected by suit- 50 able wiring as shown.

In the accompanying drawings 1 represents the exterior case to contain two coil elements 2 2 placed side by side, preferably each within a thin wooden casing and fitted

to slide into the outer case, the vibrator 3 55 being upon the front or open end, which may be provided with a suitable cover; and all electrical attachments at or near the rear or farther end thereof.

60 The separate electrical connections for primary and secondary circuits are formed by bolt screws or binding posts 17 and 18, constructed and attached to the elements in a suitable manner, preferably in a longitudinal position, and of such length that when 65 the element is placed within the case, the binding posts pass through suitable apertures 40 and 41 in the back of the case, and that binding nuts 19 and 20 and lock nuts 21, 22 placed thereon, will draw and hold the 70 element securely in place, and furnish convenient exterior attachment for the connecting wires 56, 60 to the engine.

75 The main common or return connection is formed through a metallic strip 24 technically termed bus-bar, extending across within the interior of the case 1, the connection from the elements thereto being made by springs 23 bearing thereon, one of which springs is attached to each element and in 80 suitable electrical connection with the interior windings thereof through the spring 23, and wire 52 to the vibrator.

85 The return current is conducted from the bus-bar 24 by suitable means as wire 29 to the switch 30 and thence by wires 27, 28 to binding posts 25 and 26 and by suitable wiring to the batteries.

90 This construction obviates any attachment to the front of the case, which gives a handsome appearance, easy access to the vibrators, facility of operation, and security.

95 In order to withdraw or replace an element, it is only necessary to manipulate the nuts upon the two binding posts protruding, when the element will slide out or in freely, as for examination, repairs, substitution or inspecting trouble. While in use the elements are securely held in proper place against vibration or accident.

100 The batteries, are preferably set up in two independent sets or banks of cells, 67, 68 each of which in a normal condition is capable of operating the coils. One polarity, as the positive, is connected by suitable means as wires 62, 63, and bolt 64 to the engine, and the other polarity of each battery is separately connected as by wires 58, 59 to

one of the binding posts 25 or 26 and by wires 27, 28 to plates 33, 34, of a switch 30.

My improved switch is composed of three plates, 32, 33 and 34 attached to a suitable support 30 which is provided with four holes, 35 36 37, 38 adapted to receive the switch plug 31 in such manner that said plug when in either of the holes 36 or 37 shall have electrical bearing contact upon the plate 32 and upon one of the plates 33 or 34; but when in the hole 35 the plug shall have contact upon the plate 32 and upon both plates 33 and 34. The plates 32, 33, and 34, are of such spring material that the bearing portions may have a suitable spring pressure contact upon the plug thereof.

The plates 33 and 34 are independently electrically connected through wires 27, 28 the binding posts 25 and 26 and wires 58, 59 with the batteries; also the plate 32 is connected by wire 29, or otherwise through bus-bar 24 and spring 23 with the coil; hence this plug when placed in either of the holes 36 or 37 will electrically connect the coil with one bank of batteries; but when said plug is placed in the hole 35 it connects the coil with both banks of batteries in parallel or multiple connection; giving the same electrical voltage, but the amperage current capacity of both banks of batteries combined, which is useful with weak, low or run-down batteries, or when greater power than one battery is desired. The plug 31 when placed in the hole 38 makes no connection of the switch plate, hence the batteries are open-circuited and prevented from operating or running down. The plug may be removed and carried in the pocket to prevent operation by unauthorized persons. Each element is composed of a core of iron 39, with primary winding 42, which is connected to terminal 17, the current passing through screw 9, vibrator 3, and contact spring 15, thence by wire 52 to spring 23. Over the primary is wound the secondary 43, and connected to terminal 18, and to wire 52. The condenser 50, is connected at one end to wire 51, and at the other end by wire 55 to wire 52, thereby bridging the vibrator.

The current interrupter is a vibrator consisting of a flexible spring 5 which may be provided with a weight or head 3 and having a contact point P of platinum or other suitable material. This vibrator is supported and adjusted as hereinafter described. Another spring 15 is separately supported from the case and carries an opposing or striking contact P'. These contact points constitute the electrical circuit breaker, being suitably electrically connected in the primary circuit through the springs, so that separating these points opens the circuit and interrupts the current.

The vibrator support and adjustment consists of the U-shaped body 4, of a spring

quality of metal, as shown in Figs. 1 and 2, the base portion provided with ears or feet for fastening to the case by means of screw 9, and having a flat portion 54 over its base. The vibrator spring 5 is attached thereto, by a screw 16 passing through and threaded into the block 7 clamping the vibrator spring firmly to the upper portion 54 thereof. Another screw 6 is threaded through 54 and 7, its end bearing upon the base 4 as shown in Fig. 2; hence when the screw 6 is turned to the right, its end bearing upon the stationary base 4 resisting advance, there follows a lifting effort to the portion 54 and parts suspended, which by means of the flexure of the curve 44, are tilted upward and effectively raises the vibrator, or increases the spring tension thereof. Conversely turning the screw to the left, lowers the vibrator or lessens the tension. The split and pinch screw 8 serve to clamp the screw 6 securely, yet allow adjustment.

The spring 15 is supported upon a block 13 or other support which is suitably attached to the case. The end is provided with a slot S, and is clamped firmly by a screw 14, which if loosened permits ready removal of the spring for access to the contact points or other purposes.

To examine or clean the contact points, it is only necessary to loosen the screw 14, when the spring 15 can be slipped out, leaving the lower contact in full view and both freely accessible. A bridge 10 spans over the vibrator and supports an adjustable contact screw 11 which may be screwed down to bear properly upon the vibrator to limit its upward movement, as a means of adjusting or varying the spark. The split, in connection with the pinch screw, clamps it securely yet allows adjustment.

The bridge 10 is constructed with lugs or feet and attached by screw bolts 12 with nuts in the interior of the case as shown in Fig. 2, the feet being provided with slots S so that by merely slackening these screws without removing from the nuts, the bridge may be readily slipped therefrom, and also replaced exactly without altering any adjustment, when for any reason this may be desired, as for instance, examination, cleaning, substitution or to facilitate other acts or operation.

The operation of my improved coil is as follows: The case 1 is attached in a suitable position upon the vehicle, boat or other place to be used; the elements 2, 2' being then placed within the case, and suitable wires attached to the binding posts and leading to the battery and engine as 56, 57, 58, 59, 60, 61, 62, 63 and 64. When proper connections are made and the switches on, the electric current of the battery 67 will pass to the engine at bolt 64, through the commutator 49 thereof to its selective circuit at brush 65, thence by wire 56 to the binding post of ele-

ment 2, through its primary winding 42 and vibrator, then to the terminal spring 23 and bus-bar 24 and by wire 27, to plates 34, 32, of switch 30, and return through wire 58 to the battery. In fig. 7, the switch is in position to permit only the battery 67 to act, while in figs. 1, 4, the switch is in position to allow both banks of batteries 67 & 68 to act conjointly. The electric current passing through the primary winding 42 magnetizes the core 39, and this magnetism attracts the vibrator, which by flexure of its spring, moves towards the core; but in so doing it moves away from the opposite contact, the contact points P P' separate, opening and interrupting the circuit; when the electric current ceases to flow and the core loses its magnetism, the vibrator then ceases to be attracted, and with the tension of its spring moves back to its first position, and again bringing the platinum points into contact completes the circuit, which repeats the foregoing cycle continuously as long as effective current is supplied to it. This making and interrupting of the primary current and core magnetism induces a high tension current in the secondary 43, which is led by the circuit to the sparking plug 69, 70, producing a spark 71 for igniting the engine and driving its piston 72 by the explosion of gas therein.

I have described my coil as particularly adapted to vehicles' engines, but obviously my improvements may be used for any suitable purpose. Portions may be used without the whole, or various changes or equivalent modifications may be used; as for instance, a dynamo or other source of electric current may be used, and one or more than two sources of current may be employed. The binding posts may be exterior screws with interior nuts, and may be in other than a longitudinal position. Screws may be used in lieu of springs 23. The bus-bar may be of other form, as separate wires running to the switch, or the bus-bar may form one plate of the switch. Instead of wires, other electrical connections may be employed. A pivoted or other lever may be used instead of a plug. The form of switch plates may be changed or a greater number used. The switch may be placed elsewhere than upon the case. The electric circuit may be made through the bridge and screw, or a contact or circuit conducting screw may be placed above the spring 15. The spring 15 may be supported from the bridge &c.

I use herein the term "gas engine" to include engines of an internal combustion type, whether using gaseous, or vaporous or liquid fuel.

Having thus described my improvements, I claim,—

1. In a spark coil for gas, vapor or hydrocarbon engines, an outer case containing separate insertible sparking elements, each

having a suitable vibrator upon one end, and all electrical connections at, or near the other end, some of which connections protrude through the case and are provided for external connection thereon substantially as 70 and for the purpose shown and described.

2. In a spark coil for multiple cylindered gas or vapor engines, an outer case containing separate insertible sparking elements, one for each cylinder, and each having a suitable 75 vibrator upon one end, and the electrical connections at or near the other end, some of which connections protrude through the case and are provided for external connection thereon substantially as shown and de- 80 scribed.

3. The combination with a multiple spark coil for multiple cylinder engine of a case, containing separate interchangeable removable elements, each element comprising a 85 complete spark coil for a single cylinder, said elements being removable by detaching the exterior connection thereto as and for the purpose set forth.

4. In a spark coil for gas or hydrocarbon 90 engines, an outer case containing separate insertible sparking elements, each having a suitable vibrator upon one end, and all electrical connections at or near the other end, and as a common or ground connection, a 95 metallic strip within the case and springs bearing thereon, said springs being electrically connected interiorly to the pole of the element, substantially as set forth.

5. In a multiple coil for gas engines, a case 100 containing separate elements, each interchangeably removable, and connected with the primary and secondary circuits by binding posts extending longitudinally through the case and connected with the general return as ground circuit by means of a spring and bus-bar and switch, substantially as shown and described.

6. In a multiple coil for gas engines, a case 110 containing removable elements the electric connection of which comprises a longitudinal binding post for each engine circuit, and a spring connection to a bus-bar or general connection to the battery thereof, substantially as shown and described.

7. In a spark coil such as described, insertible sections provided with electric terminals, binding posts protruding through the case, and nuts thereupon securing said sections therein, substantially as specified.

8. The combination of the outer case, suitable sparking sections therein, each having primary and secondary binding posts, and return circuit including a spring upon each section, and a common bus-bar, as and for 125 the purpose specified.

9. In a spark coil the combination of removable elements, a suitable spring for the ground connection, and suitable binding posts or screws for each element, all arranged 130

- in a direction longitudinal to the axis of the element, to facilitate the removal of said element, substantially as shown and described.
10. A spark coil with removable elements, having as a common or ground connection a metallic strip attached to the inside of the case, also each element provided with a spring arranged to press upon said strip, said springs being provided with suitable electrical connections inside of the element, and the said metallic strip being electrically connected to a suitable battery.
11. A multiple sparking coil for gas engines, the elements of which are removable from said case, electric current connection thereon comprising binding posts for the batteries, wiring therefrom to a multiple switch attached thereupon, thence through a bus-bar or general connection by a spring contact to each section and suitably with the interior thereof, thence to binding posts set longitudinally in the rear of said element, substantially as shown and described.
12. In a spark coil with removable sections, one or more electric circuits provided with suitable binding posts, and said binding posts passing through apertures of the outer case, with binding nuts thereon, for the double purpose to secure the element firmly and to effect convenient exterior connection thereto, substantially as set forth.
13. In a spark coil for engines of the class herein described, an outer case containing removable elements, each with a vibrator and separate primary and secondary wire connections, and a common or ground return consisting of a metallic strip extending across the interior of the case, with suitable spring connections to each element, substantially as shown and described.
14. In a spark coil for engines of the class herein described, an outer case containing removable elements, each with a vibrator and separate primary and secondary wire connections, and a common or ground return consisting of a metallic strip extending across the interior of the case, with suitable spring connections to each element, substantially as shown and described.
15. In a spark coil as herein described, a case, separate removable elements therein, binding posts for the primary and secondary wires, and a common return through a metallic strip or bus-bar, substantially as shown and described.
16. In a spark coil as herein described, a case, separate removable elements therein, binding nuts for the primary and secondary wires and a common return through a metallic strip or bus-bar, and switch, substantially as shown and described.
17. In a spark coil as herein described, a case, separate removable elements therein, binding posts for the primary and secondary wires, and a common return through a metallic strip or bus-bar, and said binding posts positioned parallel with the longitudinal axis of the element, to facilitate removal, substantially as described.
18. In a spark coil as herein described, a case, separate removable elements therein, binding posts for the primary and secondary wires and a common return through a metallic strip or bus-bar, and said binding posts protruding through the bottom end of the case.
19. In a spark coil as herein described, a case, separate removable elements therein, binding posts for the primary and secondary wires, and a common return through a metallic strip or bus-bar the said binding posts protruding through the case, and having binding nuts to secure said elements in position.
20. In combination with a spark coil and electric circuit thereto, a primary switch which in a certain position connects one source of electric energy to the coil, and in a certain other position connects two sources of electrical energy conjointly to the coil, substantially as and for the purpose set forth.
21. In combination with a spark coil and electric circuit thereto, an electric switch which in a certain position may connect one source of electrical energy to the coil, and in a certain other position may connect two sources of electrical energy conjointly to the coil, and in another position shall open all circuits, substantially as and for the purpose described.
22. In combination with a sparking coil for gas engine, the electric current thereof supplied by batteries; an electric switch, one position of which shall complete the electric circuit of one battery singly, and in one position shall complete the circuit for two batteries conjointly, substantially as shown and described.
23. In combination with a sparking coil for gas engine, the electric current thereof which is supplied by batteries; a plug switch, one position of which shall complete the electric circuit of one battery singly, and in one position shall complete the circuit for two batteries conjointly, substantially as shown and described.
24. In combination with a sparking coil for gas engine, the electric current thereof which is supplied by batteries; a switch with springing contacts, one position of which shall complete the electric circuit of one battery singly, and in one position shall complete the circuit for two batteries conjointly, substantially as shown and described.
25. In combination with a spark coil and battery circuit thereof, a plug switch containing three or more plugging holes, two each connecting a single circuit independently,

and one connecting two circuits in multiple thereof, substantially as and for the purpose set forth.

26. In combination with a spark coil and battery circuit thereof, a circular plug switch containing four plugging holes; one not connecting the circuit, two—each connecting a single circuit, and one connecting two circuits in multiple thereof, substantially as shown and described.

27. A multiple coil composed of separate elements removably contained in a common case, said elements having three wire connections, one primary and one secondary thereof having binding posts, and the common or ground connection having a spring connection, substantially as and for the purpose shown.

28. In a spark coil, a current interrupter composed of a head supported and vibrated by a spring, said spring adjustably supported to the case, and a receiving spring independently supported to the case, these springs being in suitable electrical connection with the primary current thereof, and platinum or protected points at the contact points constituting the current breaking element, substantially as shown and described.

29. In the current interrupter portion of a spark coil, a main vibrator, one end adjustably supported from the case, its other end provided with a metallic head suspended opposite of the core, the electric breaking contact at its extreme end, and a supplementary vibrating spring, one end rigidly supported and its free end carrying the back electric contact; together with suitable electrical connections and a source of electrical energy substantially as and for the purpose shown and described.

30. In a spark coil, a vibrator support and adjustment thereof, composed of a U spring one portion of which is rigidly attached to the case, and another portion to the vibrator, and an adjusting screw for regulating said U spring in adjusting the vibrator, substantially as shown and described.

31. In a spark coil, a current interrupter composed of a vibrating spring carrying a contact point, adjustably supported by a U support of stiff spring metal, provided with an adjusting screw, and a receiving contact upon a spring independently supported, these springs being in suitable electric circuit with the primary current, and with suitably protected points thereon, constituting the current breaking element, substantially as shown and described.

32. In a spark coil vibrator, a spring, one end suitably supported from the case, the other end magnetically actuated, and carrying a current interrupting contact point, and a secondary or receiving spring, one end independently supported from the case, and an opposing contact point upon the free end,

these contact points composing the electric current interruption, substantially as and for the purpose shown and described.

33. In a spark coil, a current interrupter thereof, composed of a U support of spring material, one portion attached to the case the other portion carrying a vibrator spring, and provided with an adjusting screw, and a split and clamping screw thereof, said spring vibrating against a back contact or stop, suspended from a bridge or bar spanning said spring, substantially as shown and described.

34. A vibrator support and adjustment thereof, composed of a U spring, one part of which is rigidly secured to the vibrator, and an adjusting screw for regulating the position of said spring in order to give proper desired adjustment to the vibrator, substantially as set forth.

35. A vibrator support and adjustment thereof, composed of a U spring, one part of which is rigidly attached to the box, and the other flat part attached to the vibrator; and an adjusting screw for regulating the position of said spring, in order to give proper desired adjustment to the vibrator, substantially as set forth.

36. In a current interrupter for spark coils, a vibrating spring, one end carrying a circuit breaking contact, and the opposite end rigidly attached upon a suitable block by means of a clamping screw, and said spring being slotted to facilitate removal and replacement, substantially as and for the purpose shown and described.

37. In a spark coil, a vibrator spring secured by a screw, the screw hole thereof in the spring being slotted out, so that by loosening said screw, the vibrator may be removed without taking out the said screw, substantially as shown and described.

38. In a spark coil, a bridge supporting a contact screw, said bridge being attached by screws, the holes for said screws being slotted out so that by loosening the screws the bridge may be removed without taking out said screw, substantially as shown and described.

39. In a spark coil, in combination with necessary elements, a vibrator bridge, an adjusting screw supported therewith, and secured by a split and clamp screw, said bridge attached to the case by screws, the holes for said screws being slotted out to provide for removal of said bridge without taking out said screws, substantially as shown and described.

40. In a spark coil provided with a vibrator, a contact screw thereof supported by a bridge, said bridge being attached to the coil case by lugs secured with screws or bolts, the holes for said screws or bolts being slotted through upon one side to facilitate removal thereof.

41. In a spark coil the combination with an electric circuit therefor, a vibrator, the contact screws thereof supported by a bridge provided with lugs, said lugs secured to the case by screw bolts with nuts upon the interior of the case, the holes for said bolts being slotted to facilitate removal without removing from the nuts thereof.

42. In combination, a box or frame, a plurality of induction coils mounted therein, individual connections for the primary winding of each coil, means including a bus-bar whereby any coil can be removed from the box or frame without disturbing the primary connections of the other coils.

43. In an ignition system, the combination of a box or frame, a plurality of induction coils mounted therein, and independently removable therefrom, a source of electricity common to all the primary windings of said induction coils, electrical connections including a bus-bar connection established by the mounting of a coil in the box or frame to connect its primary coil in circuit with said source of electricity, and independent circuit connections whereby the removal of a coil from the box or frame will not affect the electrical connections to the other coils.

44. In an ignition system, the combination of a box or frame, a plurality of induction coils mounted therein and independently removable therefrom, a source of electricity common to all the primary windings of said induction coils, firing devices external of said box or frame, electrical connections including a bus bar connection established by the mounting of a coil in the box or frame to connect its primary coil in circuit with said source of electricity, and independent circuit connections whereby the removal of a coil from the box or frame will not affect the electrical connections to the other coils.

45. In an ignition system, the combination of a box or frame, a plurality of induction coils mounted therein and independently removable therefrom, an electrical contact permanently fixed in the box or frame for each induction coil, and means for mechanically fastening each coil in the box, which means also comprises an electrical connection for a terminal of the primary winding, said contacts being electrically connected together.

46. In an ignition system, the combination of a box or frame, a plurality of induction coils mounted therein and independently removable therefrom, an electrical contact permanently fixed in the box or frame for each induction coil, means for mechanically fastening each coil in the box, which means also comprises an electrical connection for the primary winding of said coil, said contacts being electrically connected together, and independent circuit connections whereby the removal of a coil from the box or frame

will affect the electrical connection to the other coils.

47. In an ignition system, the combination of a box or frame, a plurality of induction coils mounted therein, and independently removable therefrom, an electrical contact permanently fixed in the box or frame for each induction coil, means for connecting the terminal of the primary winding of each coil with said contact, said contacts being electrically connected together within or upon the box or frame and to one pole of a source of electricity.

48. In an ignition system, the combination of a box or frame, a plurality of induction coils mounted therein and independently removable therefrom, an electrical contact permanently fixed in the box or frame for each induction coil, means for connecting the primary winding of each coil with said contacts, said contacts being electrically connected together within or upon said box or frame and to one pole of a source of electricity.

49. In an apparatus of the character described, a case, a plurality of separate insertible induction coil units, primary and secondary terminals projecting from each unit, a bus-bar carried by the case arranged to make electrical connection with one terminal on each coil unit upon the insertion of the same within the case, a mechanical connection for another terminal of each coil unit to hold the latter in the case, said mechanical connection also accomplishing an electrical connection.

50. An apparatus of the character described, a case, a plurality of separate insertible induction coil units, primary and secondary terminals projecting from each unit, a circuit connector in common to all units, connected with one of the primary terminals of each unit, and independent circuit connections for the other primary terminal of each coil unit.

51. In a multiple coil for gas engines, a case containing separate elements, each interchangeably removable and connected with the primary and secondary circuits by connections extending through the case and connected with the general return or ground circuit by means of a spring, bus-bar and switch.

52. In a multiple coil for gas engines, a case containing removable elements, electrical connections for each element including a spring connection to a bus-bar or general connection to the source of electrical energy thereof.

53. A spark coil with removable elements, having as a common or ground connection a metallic strip attached to the case, also each element provided with a spring arranged to engage said strip, said springs being provided with suitable electrical connections within

each element and said metallic strip being electrically connected to a suitable source of electrical energy.

54. In a spark coil as herein described, a case, separate removable elements therein, connections for the primary and secondary wires, and a common return through a metallic strip or bus-bar.

55. In a spark coil as herein described, a case, separate removable elements therein, electrical connections for the primary and secondary wires, and a common connection through a metallic strip or bus-bar and switch to a source of electrical energy.

15 56. In an ignition system, the combination of a box or casing, a plurality of induction coils mounted therein, a contact for the primary winding of each coil mounted in the box, or casing, an electrical connector between such contacts within the box, a source of electricity, a connection between said source and said connector, a contact on each coil adapted to engage one of said connected contacts to connect its primary winding in

25 circuit with said source of electricity, and independent circuit connections whereby the removal of a coil from the box or frame shall not affect the electrical connections to the other coils.

57. In an ignition system, the combination of a box or casing, a plurality of induction coils mounted therein, a contact for the primary winding of each coil mounted in the box or casing, an electrical connector between said contacts, a source of electricity, a connection between said source and said connector, firing devices external to said box or casing, a contact on each coil adapted to engage one of said connected contacts to connect its primary winding in circuit with said source of electricity, and independent circuit connections whereby the removal of a coil from the box or casing will not affect the electrical connections to the other coils.
